A. J. HARRIS

LET-OFF MEANS FOR LOOMS

Filed Dec. 29, 1923

UNITED STATES PATENT OFFICE.

ARTHUR J. HARRIS, OF PATERSON, NEW JERSEY.

LET-OFF MEANS FOR LOOMS.

Application filed December 29, 1923. Serial No. 683,349.

To all whom it may concern:

Be it known that I, ARTHUR J. HARRIS, a citizen of the United States, residing at Paterson, in the county of Passaic and State 5 of New Jersey, have invented certain new and useful Improvements in Let-Off Means for Looms, of which the following is a specification.

The object of this invention is to provide 10 a let-off mechanism for looms whereby an equable tension will at all times be maintained on the warp and the goods woven will be free of blemishes characterized by irregular spacing of the weft or filling and 15 due in the ordinary loom to the employment of slip-friction as a medium of resistance to the rotation of the warp-beam. Given an instrumentality to pull the warp forward and a rotary warp beam structure, 20 together with a support on which said structure is journaled, the invention contemplates an actuated means in the support normally holding said structure against rotation under the pull of the warp but adapted 25 to be moved to permit such rotation, an oscillating actuating means periodically engageable with the actuated means to cause such movement of the latter, the part of one of said means which is engaged by the other 30 being shiftable into and out of position for such engagement, and means, normally maintaining a bend in the warp between said instrumentality and said structure and yieldable transversely of and with the warp 35 when the latter tightens, for controlling the shifting of said part. It also contemplates, given such instrumentality, beam structure and support, means to control the rotation of said structure in the direction to pay out 40 the warp including a tension-beam extending transversely of and maintaining a bend in and yieldable transversely of and with the warp, and means to preserve the first-named means during its movements with 45 the axis of the tension-beam always substantially parallel to a given line.

In the accompanying drawing,

Fig. 1 is a side elevation of a loom embodying the present invention;

Fig. 2 is a plan view of the mechanism constituting the invention; and

Fig. 3 is a rear elevation of a part of what is shown in Fig. 1.

In the loom frame *a* is the breast beam *b* 55 and a roller *c* over which the warp *A* ex-

tends, the same at *B* having incorporated with it the filling or weft so as to form the fabric. There is a suitable take-up means, here represented by a sand-roller *d* (having a ratchet *e* and a pawl *f* to prevent the 60 backward rotation thereof). *h* is a going part of the loom, as its crank-shaft, and *h'* is an eccentric thereon.

Rearward of the loom is a pair of standards *i* which form a fixed support in which 65 are journaled the gudgeons of the beam-structure *k*. These gudgeons are actually journaled in forwardly and downwardly inclined notches *l* permitting the removal of the beam, as will appear.

The beam-structure includes as a fixed 70 part thereof a worm-wheel *m* and with this worm-wheel meshes a worm *n* fixed to rotate with a horizontal shaft *o* (by a set-screw *p*) extending at right angles to and 75 arranged above the axis of the beam and journaled in a bearing *q* on one of the standards *i*. (The beam may be removed from its bearings by releasing the set-screw *p* and rotating the worm until it clears the 80 worm-wheel and may be removed from shaft *o*.) On shaft *o* is fixed a ratchet wheel *r* with which engages a pawl *s* pivoted in a lever *t* which is fulcrumed on the 85 shaft *o*. Parts *n*, *o*, *r*, *s* and *t* constitute 90 the aforesaid actuated means normally holding the beam structure against rotation under the pull of the warp and adapted to be moved, as by vibrating the lever *t* to cause the pawl to rotate the ratchet wheel 95 and consequently the worm step by step, to permit such rotation. The lever is normally held depressed by gravity, tending to rest on a screw stud *t'*.

The oscillating actuating means periodically engageable with said actuated means to cause movement thereof here takes the form of a flat sliding bar or dagger *u* which is confined to a vertical plane of movement by a guide *v* on the side of the loom frame and at its forward end has a strap *x* which 100 embraces the eccentric *h'*; the upper edge of said bar is at the rear end inclined to form a cam surface as shown in Fig. 1 and is adapted, while the bar is being oscillated by the eccentric, to wipe against the under side of lever *t* and thus vibrate the same. The bar or dagger is shiftable up and down into and out of position as it oscillates thus to 105 wipe against or engage said lever *t*, being 110

normally held down, or out of such position, by gravity.

The means for controlling the shifting of the bar or dagger is as follows: A tension-beam γ rests on the warp between the roller c and the warp-beam and tends to maintain a bend in the warp, as shown. On the ends of its shaft z are fixed two pinions 2 which mesh with racks 3 on brackets 4 projecting rearwardly from the loom sides, so that in the vertical movements of the tension-beam its axis is always preserved parallel with a given line and (it being assumed that the beam k and roller c have their axes parallel with that of the tension-beam) the tension-beam will thus preserve equal tension on all parts of the warp transversely thereof. (To prevent rubbing the warp, the tension-beam may be freely revoluble on the shaft z between collars z' thereon.) The shaft is journaled at its ends in two slides 5 which have upper and lower pairs of rearward projections 5^a inturned to embrace the racks 3 (see Fig. 2) and thus retain the pinions in engagement with the latter, each slide having suspended therefrom a weight 6 and the near slide in Fig. 1 having an arm 5^b (as shown in Fig. 2) on which is a grooved roller 5^c to upwardly bear against the under side of the dagger u .

When the loom is operating, shaft h being rotated, the dagger is oscillated. The beam structure normally tends to be held against rotation to pay out the warp by the actuated means $n-o-r-s-t$ which remains at rest (the lever t resting on stud t') so long as the controlling means including the tension-beam is not elevated to an extent sufficient to shift the actuating means u into position to engage the lever t ; but whenever, the bend in the warp being taken up, this occurs, the actuating means actuates the actuated means and bring about the movement thereof necessary to permit the beam structure to rotate and thus pay out more warp. Each time there occurs a momentary paying out of warp, corresponding to an increment of advance of the ratchet wheel, the controlling means maintains the tension

on the warp, so that at all times the tension 50 remains constant.

Having thus fully described my invention, what I claim as new and desire to secure by Letters Patent is:—

1. In combination, an instrumentality to pull the warp forward, a rotary warp beam structure, a support on which said structure is journaled, an actuated means in the support normally holding said structure against rotation under the pull of the warp but adapted to be moved to permit such rotation, an oscillating actuating means movable periodically into engagement with the actuated means to cause such movement of the latter, one of said means including a cam affording such engagement and the part of one of said means which is engaged by the other being shiftable into and out of position for such engagement, and means, normally maintaining a bend in the warp between said instrumentality and said structure and yieldable transversely of and with the warp when the latter tightens, for controlling the shifting of said part. 55 60 65 70 75

2. In combination, an instrumentality to pull the warp forward, a rotary warp beam structure, a support on which said structure is journaled, an actuated means in the support normally holding said structure against rotation under the pull of the warp but adapted to be moved to permit such rotation, an oscillating actuating means movable periodically into engagement with the actuated means to cause such movement of the latter, one of said means including a cam affording such engagement and the part of one of said means which is engaged by the other being shiftable into and out of and normally held out of position for such engagement, and means to shift said part into said position normally maintaining a bend in the warp between said instrumentality and said structure and yieldable transversely of and with the warp into shifting engagement with said part. 80 85 90 95

In testimony whereof I affix my signature.

ARTHUR J. HARRIS.
